(57) **CLAIM**

We claim the ornamental design for the vertical arc trainer, as shown.

DESCRIPTION

FIG. 1 is a rear, right side perspective view;

FIG. 2 is a front, left side perspective view;

FIG. 3 is a rear elevational view;

FIG. 4 is a front elevational view;

FIG. 5 is a right side elevational view, the left side being a mirror image thereof; and,

FIG. 6 is a top plan view.

The broken line showing of the control panel is included for the purpose of illustrating environmental structure and forms no part of the claimed design.
